UNITED STATES PATENT OFFICE

WILLIAM LUTHER SMITH, OF MIAMI, FLORIDA

VENETIAN BLIND

Application filed December 29, 1932. Serial No. 649,389.

This invention relates to sun shades of the type generally known as "Venetian" blinds.

Devices of this kind have been produced of slats supported by flexible straps and operating cords have been used for raising the blinds, during which operation these slats have been drawn together into a compact bundle.

Where the blinds have been of large sizes and the slats correspondingly heavy, difficulty usually has been experienced in so mounting the operating cords as to permit the blind to be raised easily.

Furthermore in structures thus far devised the top or "tilt" rail of the blind has not been easily removable to permit bodily removal of the entire blind without disturbing the hardware used for supporting and guiding the blind.

It is an object of the present invention to overcome the disadvantages present in prior structures by providing a "Venetian" blind all parts of which are so mounted in their supports and guides as to permit quick and easy removal of the blind without disturbing the hardware used therewith.

It is a further object to provide an arrangement of operating cord and cooperating pulleys whereby the cord can be operated easily and minimum force is required in the lifting of blinds of the largest sizes.

With the foregoing and other objects in view which will appear as the description proceeds, the invention consists of certain novel details of construction and combinations of parts hereinafter more fully described and pointed out in the claims, it being understood that changes may be made in the construction and arrangement of the parts without departing from the spirit of the invention.

In the accompanying drawings the preferred form of the invention has been shown.

In said drawings:

Figure 1 is a front elevation of the "Venetian" blind and its guiding and supporting structure, a portion of this latter structure being in section and the blind being shown partly raised.

Figure 2 is a side elevation of the structure shown in Figure 1.

Figure 3 is a plan view.

Figure 4 is a section on line 4-4 Figure 1.

Figure 5 is a section on line 5-5 Figure 1.

Figure 6 is a section on line 6-6 Figure 1.

Figure 7 is a bottom plan view of the intermediate cord guide used on the top rail.

Figure 8 is a side elevation thereof.

Figure 9 is a plan view of one end portion of the bottom rail of the blind.

Referring to the figures by characters of reference 1 designates the top member of the frame of the blind and this member is formed in its top face with a longitudinal channel 2 extending from one end to the other thereof. As shown in Figure 1 the channel has each end inclined downwardly at 3 to an end slot 4 opening downwardly into a guide channel 5 formed in the inner side of the side strip 6 of the blind frame. The two side strips, in turn, are supported on and secured to the bottom member 7 of the frame.

The blind is made with a bottom rail 8 the ends of which are reduced in width as at 9 so as to project into and slide freely within the channel 5.

A top rail 10 is provided with trunnions 11 and 12 which do not project into the channels 5, this being possible because of the fact that top or tilt rail 10 is considerably shorter than bottom rail 8.

The trunnion 11 is removably supported in a bracket 13 secured to the top member 1 and depending therefrom, there being an angular slot 14 in this bracket whereby the trunnion 11 can be inserted and removed readily in the same manner as a window shade roller of the ordinary construction.

Trunnion 12 is movably seated in the housing 15 of the tilt mechanism commonly employed and which is actuated as usual by cords 16. As this tilt mechanism constitutes no part of the present invention it is not deemed necessary to show or describe it. It might be stated at this time that the trunnion 12 is detachably connected to the top bar

or rail 10 so that by detaching said trunnion from the rail said rail can be lifted readily from position in the blind frame.

Flexible loops or straps 17 are secured to the top or tilt rail 10 and to the bottom rail 8 and are suitably joined to slats 18 which are extended through the loops and are in superposed relation. Each slat has end lugs 19 which extend into the channels 5 and permit the slats to slide and to tilt relative to the frame.

Secured on the top member 1 at a point between the ends thereof is a plate 20 which overlies a recess 21 in said member and communicating with channel 2. To the bottom of this plate is secured a bracket 22 which operates with plate 20 to hold spaced guide pulleys 23 mounted for rotation about vertical axes.

23 A tongue 24 is extended from the plate 20 laterally beyond member 1 and has depending ears 25 between which is supported a guide pulley 26 mounted for rotation about a horizontal axis.

25 Additional guide pulleys 27 are mounted within the enlarged end portions of the channel 2 and secured to the ends of the bottom rail 8 are brackets 28 each of which carries a guide pulley 29.

28 An operating cord 30 is secured at its ends to the upper end portions of the respective side strips 6, as shown at 31. From these points of connection the cord is extended downwardly within channels 5 and under pulleys 29 from which it is extended upwardly within said channels 5 to the pulleys 27. The cord extends thence to the pulleys 23 and is looped as at 32, the said loop being guided over pulley 26 and extended downwardly to a fastening stud 33 or the like located on one side portion of the frame.

When the loop 32 is disengaged from the stud 33 the bottom rail 8 and slats 18 will move downwardly by gravity, causing the strips or loops 17 to become taut. While the parts are thus located in their lowered or closed positions said slats can be tilted in either direction to any desired angle by tilting rail 10 in the usual manner.

30 By pulling on the loop 32 the end portions of the cord will exert lifting forces upon the pulleys 29 and will cause bottom rail 8 to move upwardly and produce a corresponding upward movement of the slats in regular succession. During this operation the ends of the bottom rail and the lugs 19 on the ends of the slats will ride in the channels 5.

By mounting the operating cord as described the power exerted is multiplied to such an extent that "Venetian" blinds of the largest sizes can be raised easily by anyone and the difficulties heretofore encountered in operating large and heavy blinds of this type are overcome.

65 A feature of primary importance is found

in the fact that by detaching trunnion 12 from the tilt rail 10 said rail can be disengaged from bracket 13 and all of the slats, as well as the bottom rail 8, can be tilted and removed from channels 5, the pulleys 29, at this time, lifting out of the loops formed by the end portions of the operating cord 30. Thus the blind is advantageous as compared with other makes of "Venetian" blinds because of the ease with which it can be removed from and placed in position when desired.

What is claimed is:

1. The combination with a frame having guide channels on the sides thereof, an operating cord having its ends secured fixedly adjacent to the upper ends of the channels, said cord providing end loops supported within the respective channels and an intermediate loop, of guide pulleys connected to the top of the frame for guiding the cord from said intermediate loop along said top and to the loops within the channels, a "Venetian" blind having a top rail detachably supported from the top of the frame and out of engagement with the sides of the frame, a bottom rail slideable within the channels, pulleys carried by the ends of the bottom rail and removably seated in the channels, said pulleys being movably supported by the loops in the channels, and slats interposed between and movably connected to the top and bottom rails, said slats being in slideable and removable engagement with the channeled sides of the frame.

2. The combination with a frame having channeled sides and a channeled top, of a cord secured at its ends adjacent to the upper ends of the channels in the sides, a plate secured to the top frame, spaced pulleys carried thereby and extending into the top channel, a guide pulley supported by said plate and spaced from the frame, guide pulleys in the ends of the top channel, said cord being looped within the side channels and extended over the last named pulleys into

engagement with the spaced pulleys on the plate, said cord having an intermediate loop extending between the spaced pulleys and over and depending from the guide pulley on the plate, and a "Venetian" blind comprising

a bottom rail removably and slidably mounted at its ends in the side channels, pulleys on said ends movably supported by the loops in the side channels, a tilt rail removably supported by the top of the frame and clear of the sides of the frame, and slats between and movably connected to the rails, each slat having terminal lugs slidably and removably seated in the side channels.

In testimony that I claim the foregoing as my own, I have hereto affixed my signature.

WILLIAM LUTHER SMITH.
